CLAIM

The ornamental design for a mobile phone, as shown and described.

DESCRIPTION

FIG. 1 is a front perspective view of a mobile phone showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The outermost broken line of the speaker opening, which is within the claimed surface, is immediately adjacent to the shaded areas, and defines a region that is unshaded, represents the bounds of the claim. All other broken lines, including the tiny circles near the speaker, the rectangle that indicates the display, and the features within the outermost boundary of the speaker, show portions of the mobile phone that form no part of the claimed design. The broken lines form no part of the claimed design.
